US00D844673S

(12) **United States Design Patent** (10) **Patent No.:** **US D844,673 S**
Stolarski (45) **Date of Patent:** **** Apr. 2, 2019**

(54) SNOWPLOW	6,526,677 B1 *	3/2003 Bloxdorf	E01H 5/06
(71) Applicant: SAMASZ SP. Z.O.O. , Zabludow (PL)	6,594,923 B1	7/2003 Kost et al.	37/231
(72) Inventor: Antoni Stolarski , Bialystok (PL)	6,615,513 B2	9/2003 Quenzi et al.	
(73) Assignee: SAMASZ SP. Z O.O. , Bialystok (PL)	6,711,837 B2	3/2004 Bloxdorf et al.	
(**) Term: 15 Years	6,860,039 B2	3/2005 Schultz et al.	
(21) Appl. No.: 29/628,980	6,874,582 B2	4/2005 Hollinrake et al.	
(22) Filed: Dec. 9, 2017	6,928,757 B2	8/2005 Bloxdorf et al.	
(51) LOC (11) Cl. 15-03	6,941,685 B2 *	9/2005 Goy	E01H 5/06
(52) U.S. Cl. USPC D15/11	6,944,978 B2	9/2005 LeBlond et al.	172/816
(58) Field of Classification Search USPC ..... D15/10, 11, 22-28, 32; 37/196, 266 CPC ..... E01H 5/06-5/062; E02F 3/76-3/848 See application file for complete search history.	6,964,121 B2	11/2005 Harris	
	7,134,227 B2	11/2006 Quenzi et al.	
	7,171,769 B2	2/2007 Schultz et al.	
	7,171,770 B2	2/2007 Schultz et al.	
	7,191,846 B2 *	3/2007 Matsumoto	E02F 3/815

FIG. 1 is a front top left side perspective view of snowplow showing my new design;

FIG. 2 is a front top right side perspective view thereof;

FIG. 3 is a rear top left side perspective view thereof;

FIG. 4 is a left side elevational view thereof;

FIG. 5 is a rear elevational view thereof; and,

FIG. 6 is a top plan view thereof.

1 Claim, 6 Drawing Sheets
